CHARLES MARTIN MALLORY, OF CHATTANOOGA, TENNESSEE, ASSIGNOR OF ONE-HALF
TO EARL C. MALLORY, OF INDIANAPOLIS, INDIANA.

METHOD OF AND MEANS FOR MAKING MOLDS.

Application filed July 28, 1926. Serial No. 125,544.

This invention relates generally to the subject of mold-making by the use of patterns, and producing articles in large quantities corresponding to the molds, the invention 5 having reference more particularly to a method of making sand molds and to means for practicing the method.

An object of the invention is to provide a method for rapidly making molds of sand 10 or other suitable substances for cheaply and economically producing castings of metal or other substances, in order to be enabled to market production at low cost.

Another object is to provide an improved 15 method of making sand molds whereby the slow and tedious practice of ramming sand in flasks shall be eliminated; whereby also the use of troublesome separate bottom boards may be obviated and also less sand 20 be required than hitherto commonly used, with a saving of time and labor for recleaning sand; and whereby the use of troublesome parting sand may be eliminated with a saving in expense.

25 A further object is to provide a method of making sand molds whereby drag and cope flasks may be used and expeditiously brought together to match mold parts without entailing the troublesome use of flask pins 30 or dowels usually made use of, and whereby various mold-making operations may be facilitated and economical results obtained.

A still further object is to provide improved flasks and other devices which shall 35 be of such construction as to be adapted for carrying out the new method of making molds, as a means co-related to the method whereby the most advantageous results may be obtained.

40 With the above-mentioned and other objects in view, the invention consists in a method comprising an improved mold and in various steps in sequence to be taken in the formation of a patterned mold to receive 45 molten or semi-liquid substances to obtain a casting; the invention consisting also further in a method of using a mold, and in a novel flask and a method of using it, as hereinafter particularly described and further 50 defined in the accompanying claims.

Referring to the drawings,—Figure 1 is 55 a perspective view of a two-part flask and a means for controlling it comprised in the invention, being illustrative of feasibility rather than of arbitrary construction; Fig.

2 is a perspective view of the flask having a mold therein made in conformity to the invention; Fig. 3 is a vertical sectional elevation of the mold and pattern therein, the several parts being adjusted for receiving 60 mold-forming substances such as sand; Fig. 4 is a top plan of Fig. 1 partially broken away to expose details and a modification of elements; and, Fig. 5 is a fragmentary plan of other modifications of feasible structural 65 details which may be varied in practically attaining the objects of invention.

Similar reference characters in the different figures of the drawings indicate corresponding elements or features of construction herein referred to in detail.

Various mechanical elements may be made use of in practically carrying out the method comprised in the invention, but for descriptive purposes it is deemed sufficient to illustrate an improved two-part flask having novel features necessary to the attainment of the objects of the invention to a very high degree, the flask not being limited, however, to two parts, the drag and the cope of the 80 flask being shown.

In practically carrying out the objects of invention a suitable base plate 1 is provided which has parallel guide bars 2 and 3 on its top, to guide the parts of a flask, being a 85 convenient means for the purpose, but a guide may be otherwise constituted. The guide may be in the form of the top of a truck having small wheels 4, 4' at one end thereof and legs 5, 5' at the opposite end. 90 The end that is supported by the wheels has standards 6, 6' rigid thereon to support one part of a molding-flask.

In making sand molds for simple castings, especially plates, a flask having only a drag 95 and a cope commonly is required and is deemed sufficient for explanations of the invention. Specifically, the drag comprises wall portions 7, 8, 9, 10, each wall portion having a bevel face 11 on the inner side 100 of the end that is to receive the molding sand. The wall portion 7 is arranged on the base 1 to guide the drag which is stopped against the standards. The drag is provided with a pressure-equalizing bottom 105 which has openings therein, the bottom being desired as a backing to the sand and the openings permitting the escape of sufficient sand while a mold is being made, to equalize pressure and insure uniformly compact sand. 110

The bottom may be composed of bars 12 that are triangular in cross-section and arranged with an apex thereof towards the receiving end of the drag, the bars being cast with or fixed to the wall portions thereof. The bars are located more or less distant from the receiving end of the drag, depending upon the depth of the mold required, and they may be all on one plane or 5 may be arranged otherwise to conform to varying thickness, curvature, or other contour of the pattern, in order to avoid the use of an excessive quantity of sand. When the drag is sufficiently large to require very 10 long bars, brace bars 13 and 14 are provided which are fixed to the side walls and aid in supporting the drag bottom. The cope is generally similar to the drag, having wall portions 7', 8', 9', 10', and bevel portion 11', 15 the bottom composed of bars 12' suitably spaced apart, and braces 13' and 14', the wall portion 7' being movably guided upon the base 1 and between the guide bars 2, 3, so that the cope may be moved accurately to or 20 from the drag. The cope has a gate box 15, preferably in one corner, and the box has a bottom in which is an aperture 16 to receive a gate-molding pin, commonly termed a sprue in horizontal arrangement, 25 the box 15 being in the higher portion of the cope as arranged when making a mold.

A suitable match-plate 17 is made use of which has a pattern 18 secured to one side thereof and in some cases a pattern 19 on its 30 opposite side, the patterns being of such design as may be required. The match-plate is removably arranged on edge on the base 1 and preferably extends outwardly over and beyond the guides 2 and 3, the pattern and its holder being between the two 35 parts of the flask when making a mold. A sprue 20 is arranged in the aperture 16 with its smaller end against the pattern or a gate extension thereof and yieldingly held in place by a coil spring 21 seated on its outer end and also against a pivoted bar 22 on the box 15 or other portion of the cope. Thus when the two parts of the flask are 40 separated they may receive molding-sand 45 on opposite sides of the pattern.

In order to confine the sand as it is piled up between the parts of the flask, suitable boxing sides are provided and adapted for cooperating with the vertical portions of the flask parts, preferably comprising a side plate composed of two sections 23 and 24 secured to one vertical edge portion of the match-plate with guiding contact against the wall portions 8 and 8', and a similar 50 plate composed of two parts 23' and 24' secured to the opposite edge portion of the match-plate in guiding a contact with the wall portions 9 and 9', the side plates being guided also upon the tops of the bars 2 and 55 3 to maintain the match-plate in upright

position when making ready to introduce the sand for the mold. The sand is to be introduced into the opening between the higher wall portions 10 and 10' usually by means of a shaker 25 having a sieve 26 therein, to be manipulated as may be desired, whether by hand or by machinery, but permitting the removal of the flask from beneath it. 70

As an example of a flask bottom a plate 75 27 is shown as fixed to wall portions of the flask and it has perforations 28 therein, each perforation having a countersink 29 in the end in which the sand is to be received.

As an example of means whereby the two 80 parts of the flask may be forced together to compress the molding-sand, the guide base 1 is shown as having an abutment 30 rigidly fixed thereon and in which a screw 31 is arranged to be operated by a hand wheel 32 85 fixed to the outer end thereof, a head plate 33 being swiveled on the opposite inner end of the screw, the head plate preferably being provided with a lever arm 34 whereby to turn it on the screw. The head plate is arranged to bear against the back of the cope, and it has lugs 35 and 36 oppositely arranged on its bearing face and so as to enter lug holes 37 and 38 respectively in the brace bar 13', enabling the screw to draw the cope 95 away from the drag.

In Fig. 2 the flask is shown on a floor with a sand mold 39 in the drag supported on the bottom thereof and the matching mold 40 in the cope backed by the novel bottom 100 therein, the mold cavity 41 being so represented as to receive the molten metal through a gate 42 which has been provided in sand 43 packed in the box 15. In practicing the method with the novel means provided, the 105 several elements being arranged as shown in Figs. 1, 3 and 4, sand is introduced simultaneously into the two flask parts at their parting sides on opposite sides of the match-plate and the pattern and confined in bulk 110 or mass form until the flask parts are filled to their bottoms, after which pressure is applied to compress the sand, by the means illustrated the cope only being moved, causing the match-plate to be moved towards the 115 drag and the cope towards it and finally to the match-plate, the latter being similarly moved entirely to the drag, excessive pressure on portions of the sand causing particles to escape through the openings in the 120 flask bottoms until the density of the sand is sufficiently uniform for making a proper sand mold. After completing the compressing operations, the sprue 20 will be found to have been pushed outward further into its 125 box, so that the spring may be removed from it and sand may be packed around it so as to form a gate after withdrawal of the sprue. The pattern and its supporting match-plate is withdrawn with the side 130

plates thereon after separating the flask parts, and the flask parts are brought together so as to complete the mold, after which the truck may be tilted up and the flask may be readily removed therefrom and placed upon a floor ready for pouring metal into the mold. After a casting has been made and the sand knocked out of the flask parts the quantity of sand to be recleaned 10 for further use will be found to be much less than hitherto.

What is claimed as new is:

1. The method of making sand molds which consists in compactly pressing sand to 15 opposite sides of a pattern and simultaneously discarding surplusage sand from the back of the molds.

2. The method of making sand molds which consists in supporting a pattern between separated flask parts, in simultaneously pressing sand in the flask parts and discarding surplusage sand and thereby causing uniform density of sand on the pattern.

3. A method of making molds by confining a bulk of mold-forming substance about a freely-shiftable pattern, forcibly bringing flask parts into the bulk of the substance and thereby filling the flask parts and pressing the substance compactly with equalized 30 pressure to the pattern by discarding surplusage substance, and in removing the pattern from the substance.

4. A method of making molds which consists in supporting a pattern to freely shift 35 between two flask parts, introducing a mold-forming substance simultaneously to opposite sides of the pattern and into the flask parts at the sides that are towards the pattern, in confining the substance between the flask parts, creating pressure on the substance by means of the flask parts, discarding surplusage substance, compactly pressing the substance to the pattern, and finally removing the pattern from the substance.

5. A method of making molds which consists in setting up a pattern edgewise on a match-plate to shift between separated movably guided flask parts, each flask part being adapted to equalize sand-pressure therein, applying mold-forming material simultaneously to the two opposite sides of the match-plate and simultaneously to the interior of the flask parts, creating equalized pressure on the material by discarding surplusage 50 material by means of the flask parts and simultaneously pressing the material about the pattern by forcing the flask parts together, and finally removing the pattern with the match-plate from the material.

6. The method of making a sand mold which consists in simultaneously filling the drag and the cope of a flask while separated and applying the sand to a pattern on a match-plate shiftably guided between them, confining the sand, in compressing the

sand with uniform density simultaneously in the drag and the cope and about the pattern by discarding surplus sand and forcing the cope to move to the match-plate and the match-plate to move to the drag, moving 70 the cope away from the drag and the match-plate, removing the match-plate and the pattern together from the sand, and finally bringing the cope to the drag.

7. The method of making sand molds which 75 consists in arranging a flask drag and a cope part on a guide with the sand-receiving ends of the flask parts adjacently arranged and one of the parts movably guided to be shifted towards or from the other, the method including the use of flask parts provided with permanent perforate sand-discarding pressure-equalizing bottoms, in arranging a pattern fixed to a match-plate movably between the drag and the cope, in filling the drag and 80 the cope with sand at their match-plate sides and on opposite sides of the pattern, in confining the sand to the pattern, in compressing the sand uniformly by forcing the movable flask part towards the opposite part, 85 thereby causing surplus sand to be discarded through said bottoms, in withdrawing the movable flask part away from the other part and removing the pattern with the match-plate from place, and in guiding and shifting 90 the movable part to the other part of the flask.

8. Means for making sand molds including a flask part comprising wall portions, and a permanent bottom comprising pressure equalizer bars fixedly connected in parallel arrangement to opposite wall portions, the bars being spaced only slightly apart, each bar being triangular in cross-section and an apex thereof presented towards the plane of the normally front side of the flask part.

9. Means for making sand molds including a flask part provided therein with a permanent pressure equalizer bottom to support sand in the flask part and having tapered apertures mainly to retain the sand and adapted for the escape of surplusage sand, means to temporarily support a pattern at a distance from the front of the flask part and opposite to the pressure equalizer bottom, means to confine the sand to the pattern, and means to press the pattern into sand in the flask part and to compress the sand.

10. Means for making sand molds including two co-operating pressure-equalizing flask parts having wall portions adapted to be directly supported and guided to movably support the flask parts with their parting sides on approximately vertical planes for simultaneously receiving molding sand, a match-plate to movably support a pattern between the flask parts separately therefrom, and means to movably co-operate with

115

120

125

130

the flask parts to confine sand in space between the flask parts and on the opposite sides of the match-plate.

11. Means for making sand molds including two co-operating flask parts provided each with a perforate pressure-equalizing and sand-supporting bottom, one of the flask parts having a sprue pin support therein, the flasks having guiding wall portions adapted to be directly supported and guided with the parting sides of the flasks oppositely facing on vertical parallel planes to receive sand under pressure at their parting sides with a pattern in the sand.
12. Means for making sand molds including two co-operating pressure equalizing flask parts to be arranged with their parting sides oppositely facing a vertical plane, means to guide the flask parts for accurate to-and-fro horizontal movements, means to support a pattern shiftably between the flask parts when separated to receive sand simultaneously at the parting sides of the parts, means to movably co-operate with the two flask parts to confine sand between the separated flask parts and about the pattern, and power means to force one of the two flask parts towards the other.
13. Means for making sand molds including two co-operating flask parts, means for supporting and movably guiding the flask parts with their parting sides oppositely facing a vertical plane, means to support a pattern between the flask parts, a sprue pin to be horizontally arranged in one of the flask parts and being provided with a spring co-operating with the flask part to yieldingly hold the pin to the pattern, means to

confine sand to the parting sides of the flask parts, and means to force the flask part with the sprue pin therein towards the pattern and the other of the flask parts.

14. Means for making sand molds including a flask having a drag part and a cope part provided each with an inset bottom having apertures therein to constitute a sand pressure equalizer and backing, a guiding base for the flask parts to support them with their parting sides arranged on opposite sides of an approximately vertical plane, means to support a pattern between the drag part and the cope part, means to introduce sand to the two flask parts at their parting sides, and means to force one of the flask parts towards the other and compress the sand with the pattern therein.

15. In means for making sand molds, the combination of a drag and a cope provided each with a pressure-equalizing bottom, means to bodily support the drag and the cope in co-operative to-and-fro sliding arrangement with their parting sides perpendicular to the support, a pattern and means to bodily support it movably between the drag and the cope separately therefrom, means to sift sand into space between the drag and the cope and simultaneously about the pattern, means to co-operate slidably with the drag and the cope to confine the sand at the parting sides of the drag and the cope, and power means for pressing the sand simultaneously to the pattern and in the parting sides of the drag and the cope.

In testimony whereof, I affix my signature on the 20th day of July, 1926.

CHARLES MARTIN MALLORY.
